United States Patent Office

Des. 197,925
Patented Apr. 7, 1964

197,925

DISPENSING CONTAINER

Richard C. Allen, Glen Ellyn, Ill., assignor to Continental Can Company, Inc., New York, N.Y., a corporation of New York

Filed July 26, 1963, Ser. No. 75,993

Term of patent 14 years

(Cl. D58—17)

FIG.1

3

4

I claim:

The ornamental design for a dispensing container, as shown.
